UNITED STATES PATENT OFFICE

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON

FEEDING DEVICE FOR STUFFING MACHINES

Application filed June 21, 1929. Serial No. 372,661.

My invention relates to a newspaper stuffing machine, by which is meant a machine for assembling or stuffing newspapers.

One of the objects of the invention is to provide a practical and advantageous machine for the purpose.

Another object of the invention is to secure efficiency, effectiveness and speed in machines of this character.

10 Another object of the invention is to avoid crumpling the papers or sections in the stuffing process, to prevent jams and clogging the machine and so interfering with or stopping the whole process.

15 Another object of the invention is to permit the effective handling of paper sections of various kinds of paper, thin, medium, filmy, thick and so on, and particularly to prevent trouble when thin and filmy paper is used.

Another object of the invention is to provide a simple, advantageous and effective mechanism for inserting one or more inner or 20 insert sections of the newspaper, into an outer or cover section.

Other objects of the invention are to secure the foregoing and other useful ends in a simple and expeditious manner.

In the drawings:

30 Fig. 1 is a side view of part of a stuffing machine with certain parts in section.

Fig. 2 is a section at the line 2—2 of Fig. 1.

Fig. 3 is a plan of a portion of the conveyor bed.

35 Fig. 4 is a detail in plan of a carrier frame.

Fig. 5 is a longitudinal section showing the carrier frame and its operating mechanism.

Fig. 6 is a section at the line 6—6 of Fig. 3.

40 Figs. 7, 8 and 9 are details showing the feeder arm and the tracker bar in various positions.

The drawings show the stuffing mechanism which is the particular subject of this invention, as applied to a stuffing machine arranged to handle a multiplicity of sections of newspapers, such as, for instance, the ad. section, the editorial section, the fashion, sports and cover sections, or as many as there happen to be in any particular publication to be handled by the machine.

Fig. 1 shows what may be termed a magazine which is indicated as having the paper stack holders 10—11—12 and 13, and supports 14 and 15. This particular magazine is what is to be understood as storage for the cover sections and is similar to the magazines for the insert section (these latter not here shown and not a part of this invention) having been caused to deposit their contents on a conveyor bed indicated at 16, and propelled or conveyed toward the cover-section magazine by the conveyor chain 17 which has the 55 tappets 18.

It now having been explained that the insert sections are brought to the locality of the cover sections, the operation of the cover section magazine will be described in general. The support 14 is stationary. The support 15 which is movable and, pivoted at 20, is caused to retract by the action of cams (not shown) mounted on the shaft 21. The paper section is gripped between a roller 22 and a segment 23 and then carried along thereby in the path determined by the guide 24, then entering between the rollers 25 and 26 from and by which it is conveyed to the attrition segments 27 and 28 on the shafts 29 and 30. At this point the cover section is held in an open position by mechanism not shown in this application because it constitutes no part 70 of the present invention. The shaft 29 is interconnected to the shaft 17^a of the conveyor 75 17, and also to the shaft 30 in any convenient manner (not shown) and is driven by any available source of power (not shown). The shaft 29 has mounted at one end thereof a short crank arm 31 having a wrist-pin 32 arranged to translate the rotary motion of the shaft 29 to reciprocating motion in the connecting arm 33 which operates, through the bell crank 34, the connecting rod 35. This rod is attached at 36 to a short arm 37 for operating the shaft 38 which is mounted for rocking in journals 38^a—38^b which are supported on the main frame of the machine. This motion is transmitted and multiplied to and by the long lever 39 for operating the feeder devices. The arm 39 has, connected at 40, the rod 41 which carries a spur pinion 42 journalled on 80

95 38^a—38^b which are supported on the main frame of the machine. This motion is transmitted and multiplied to and by the long lever 39 for operating the feeder devices. The arm 39 has, connected at 40, the rod 41 which carries a spur pinion 42 journalled on 100

the shaft 43; this shaft 43 is fixed in the members 44—44 of the forked rod-head 45. The pinion 42 is arranged to mesh with a stationary rack 46 and a movable rack 47. To insure the proper relation of the teeth of the rack 46 and the pinion 42, the guide rollers 49—49 are provided whose diameters are equal to the diameter of the pitch circle of the pinion 42 and which roll on guide rails 50—50 placed on a level with the pitch line of the teeth in the rack 46. The rollers and pinion are preferably fastened together as by rivets 51 to rotate as one unit.

A pedestal 52 supports the tracks 50—50, the rack 46 and also the U-shaped brackets 52^a—52^a. These brackets 52^a also furnish supports for the guide members 53—53 which have tongue and groove engagements at 54 and 55, the grooves 55 being in the sides 20 of the rack 47. The members 53 are secured by bolts 53^a to the brackets 52^a.

The rack 47 has secured to it the frame A, which is composed of the cross bars 60 and 61 which are secured to the rack 47 for movement therewith at 62—62 and longitudinal members 63—63 which are guided on either side of the members 53—53. Outside rails 64—64 extending parallel with the members 63—63 are also carried by the cross pieces 60 and 61, the members 64—64 are provided with stationary tracks 65—65. The members 63, 64 and 65 are preferably made of rectangular "stock bars", so called, as they afford finished surfaces and insure a light and 35 smoothly moving device.

Carried by the frame A are the feeder arms 70—70 pivoted at 71—71 to either side of this frame. As the frame reciprocates for feeding or stuffing the inserts into the cover sections, these arms are caused to ride on the tracker bars 72 pivoted at 73 to the stationary frame, which is supported by the member 52. The feeder arms 70 each has a roller 74, and the tracker bars 72 are located in the path of 45 these rollers and the bent or curved ends 75 cause the rollers, as they approach, to climb the tracker bar, thus raising the feeder arm above the general plane of the conveyor bed and the forked forward ends 76 of these arms 50 engage the rear edge of the insert sections and propel them forward, toward and into the cover sections.

The timing of these arms by virtue of the rack and pinion drive arrangement just described, is such that they carry the paper sections at a greater speed than the tappets 18 on the conveyor chains 17, and the timing as to speed and moment of action is such that the paper sections are carried forward, clear 60 of these tappets before they round the curve of the sprocket 17^b of the shaft 17.

In Fig. 7 is shown the roller 74 approaching the curved portion 75 of the tracker bar 72; its direction of travel is indicated by the 65 arrow B.

Fig. 8 shows the relation of the parts as the roller 74 approaches the end of its travel, the extreme end being indicated by the dotted position of the roller 74, the arm being held in raised position by its engagement with the paper. Just after beginning its retracting stroke and leaving the paper, it then being unsupported, the arm falls, carrying the roller in the position indicated in Fig. 8 at 74^a and is then in a plane below that occupied by the next oncoming insert section. A continued travel brings the roller underneath the tracker bar and since this bar is pivoted as at 73, it is free to swing up when the roller contacts the part 75. The frame A further 80 retracts and brings the roller entirely clear of the tracker bar and is then ready for the next excursion. The arm 70 has the end thereof chamfered at 70^b to limit its movement about its pivotal point. 85

The cross bar 61, is beveled along the edge 61^a, to prevent the frame from injuriously contacting the edge of the next oncoming insert; it will be understood that the papers, carried by the conveyor tappets 18 and the frame A, retracting to initial position are travelling with respect to each other, at a relatively high speed and necessarily so, since the frame must return the arms 70 to their extreme retracted position while the papers 90 continue to advance in an opposite direction, until the arms 70 arrive at a position just rearward of the paper insert sections which are to be acted upon as previously described. 95

It will be understood that changes and 100 modifications may be made without departing from the spirit of the invention.

I claim:—

1. In a machine of the class described, the combination with a reciprocating frame of a 105 pair of feeder arms attached to said frame arranged to engage paper sections and carry said sections forward in a horizontal plane.

2. In a machine of the class described, the combination with a reciprocating frame of a 110 pair of feeder arms, a tracker bar associated with the said arms, rollers on the arms, said rollers arranged to ride on the said tracker bar.

3. In a machine of the class described the 115 combination with a reciprocating frame, feeder arms pivotally attached to the said reciprocating frame, tracker bars attached to stationary pivots on the machine, means on the tracker bars and means on the feeder arms to control the operative position of the said feeder arms.

4. In a machine of the class described vertically operating and horizontally reciprocating feeder arms arranged to feed insert sections forward in a horizontal plane into cover sections. 120

5. In a machine of the class described, the combination with feeder arms cooperating with tracker bars having downwardly curved 125

ends arranged to raise the said feeder arms into operative position.

6. In a machine of the class described, the combination with a reciprocating frame, feeder arms pivotally attached to the said reciprocating frame, tracker bars pivotally attached to the machine, means for causing the feeder arms to travel above the tracker bars in their working stroke and means for causing the said arms to travel below the said bars in their retractive motion.

7. In a machine of the class described, the combination with a reciprocating frame, feeder arms pivotally attached to the said reciprocating frame, tracker bars pivotally attached to the machine, means for causing the feeder arms to travel above the tracker bars in their working stroke and means for causing the said arms to travel in a lower plane in their return motion.

8. In a machine of the class described, the combination with feeder arms cooperating with pivotally mounted tracker bars having downwardly curved rear ends arranged to raise the said feeder arms into an operative position.

9. In a machine of the class described, reciprocating means for stuffing insert sections into a cover section in a horizontal plane, said means including vertically oscillating feeder arms, guideways therefor in the nature of pivoted tracker bars and rack and pinion driving means associated with said feeder arms.

10. In a machine of the class described, reciprocating means for stuffing insert sections into a cover section in a horizontal plane, said means including a pair of vertically oscillating feeder bars, a connecting frame carried thereby, a pair of forked insert section engaging means at the front end of said feeder bars and tracker bars adapted to guide said feeder bars.

11. In a machine of the class described, reciprocating means for stuffing insert sections into a cover section in a horizontal plane, said means including a pair of vertically oscillating feeder bars, a connecting frame carried thereby, a pair of forked insert section engaging means at the front end of said feeder bars and tracker bars adapted to guide said feeder bars in both their forward and backward travel.

12. In a machine of the class described, the combination with a reciprocating frame, feeder arms pivotally attached to the said reciprocating frame, forked finger elements at the front end thereof, tracker bars pivotally attached to the machine, means for causing the feeder arms to travel above the tracker bars in their working stroke and means for causing the said arms to travel below the said bars in their retractive motion.

13. In a machine of the class described, the

combination with a reciprocating frame, feeder arms pivotally attached to the said reciprocating frame, forked finger elements at the front end thereof, tracker bars pivotally attached to the machine, means for causing the feeder arms to travel above the tracker bars in their working stroke and means for causing the said arms to travel in a lower plane in their return motion.

In witness whereof, I hereunto subscribe my name this 18th day of June, A. D. 1929.

SEVERIN HALVORSEN.
